UNITED STATES PATENT OFFICE

154,259

DESIGN FOR A RUBBER PLAY BALL

Joseph M. Gapstur and Richard E. Long,
Ashland, Ohio

Application June 12, 1947, Serial No. 139,602

Term of patent 14 years

(Cl. D34—15)

To all whom it may concern:

Be it known that we, Joseph M. Gapstur and Richard E. Long, citizens of the United States, residing at Ashland, in the county of Ashland and State of Ohio, have invented a new, original, and ornamental Design for Rubber Play Ball, of which the following is a specification, reference being had to the accompanying drawing, forming part thereof.

Fig. 1 is a front view of the rubber play ball showing our design;

Fig. 2 is a side view of the rubber play ball; and Fig. 3 is a rear view of the same.

We claim:

The ornamental design for a rubber play ball, as shown and described.

JOSEPH M. GAPSTUR.
RICHARD E. LONG.
